UNITED STATES PATENT OFFICE.

ARCHIBALD S. CUBITT, OF SCHENECTADY, NEW YORK, ASSIGNOR TO GENERAL ELECTRIC COMPANY, A CORPORATION OF NEW YORK.

ELECTRICALLY-CONTROLLED SWITCH.

No. 901,424.

Specification of Letters Patent.

Patented Oct. 20, 1908.

Application filed April 22, 1908. Serial No. 428,528.

To all whom it may concern:

Be it known that I, ARCHIBALD S. CUBITT, a subject of the King of Great Britain, residing at Schenectady, county of Schenectady, State of New York, have invented certain new and useful Improvements in Electrically-Controlled Switches, of which the following is a specification.

In connection with certain forms of electrical apparatus, electrically-controlled switches are used in which a current carrying coil is employed for maintaining the switch in one of its positions. This coil is often connected in a circuit in which the current is variable and serves to hold the switch in a certain position only as long as the current in the circuit and, therefore, in the holding coil exceeds a certain value. In switches of this character under certain conditions it is desirable that the current limit at which the holding coil releases may be varied by means operable from a distance.

It is an object of my invention to provide means for satisfying this need in a simple and efficient manner.

My invention is particularly adapted for use in connection with relays in which a movable core is by some means moved to a certain position and is held thereat by the magnetizing effect of a holding coil. Such relays are often employed in connection with systems of control for dynamo-electric machines in which a plurality of electrically-controlled switches are arranged to operate in succession for the purpose of effecting certain desired connections in the circuits of the controlled apparatus. For example, in certain systems of motor control now well-known to those skilled in this art the resistance interposed in the motor circuit on starting is automatically removed section-by-section by means of a plurality of electrically-controlled switches which operate successively under the control of a so-called "notching relay" which interrupts the actuating circuit for the switches after the operation of each switch and maintains said circuit interrupted as long as the current in the motor circuit exceeds a certain value. It is to these relays that my invention is especially applicable, and the need for it arises especially where, because of inequalities in the load upon the controlled apparatus, it is

desirable to vary the limit of current permissible in the circuits of the controlled apparatus and thereby regulate the rate of acceleration.

Systems of control in which the cutting out of the starting resistance in the motor circuit takes place automatically are now used to a large extent in the operation of electrically-driven vehicles, such as cars and locomotives, and it is in this line of work that my invention is especially useful.

In the following description and in the drawing I have described and illustrated a notching relay having my invention embodied therein, but I do not wish to be understood as limiting it to this application since it may be used in many other connections, as will be obvious to those familiar with this art.

The drawing illustrates in front elevation a notching relay having my invention incorporated therein.

Referring to the drawing, 1 is a back plate of any suitable insulating material upon which are mounted the various parts of the device.

2 is the iron frame of the relay secured in any suitable manner to the back plate 1, within which frame is an actuating coil 3 of insulated wire and a holding coil 4 of heavy conductor. Arranged for movement within the coils 3 and 4 is a core 5 of magnetic material carrying near its lower end a steel contact disk 6 which when the core is in the position shown bridges fixed contacts 7 and 8 of magnetic material. The contact disk 6 is slidingly arranged upon an extension 9 of the core 5 between a shoulder 10 and a spring 11. Coils 12 and 13 surround the fixed contacts 7 and 8, respectively, and are connected in series with these contacts and serve to produce a magnetic field which retains the disk 6 in engagement with the contacts 7 and 8 during the first part of the upward movement of the core, thereby delaying the opening of the contacts and also giving a quick break. A fixed core 15 of magnetic material is screwed into the top of the frame 2, being held in position by a set screw 16. This core projects into the hole through the coil 3 as shown in the drawing. A rod 17 extends upward from the movable core 5 and is connected at its

upper end to the movable member 18 of a dash-pot 19. This dash-pot allows the movable core to rise freely but retards it in its downward movement.

5 The parts of the relay so far described, except for a slight change in the rod 17, hereinafter mentioned, may be of any suitable and well-known form.

Secured in any suitable manner, either to 10 the frame 2 or directly to the back plate 1, is a frame 21 in which at 22 is pivoted a lever 23 through a hole in which the upper reduced portion 24 of the rod 17 freely passes, as clearly shown in the drawing. A 15 washer 25 may be provided on the reduced portion 24 of the rod 17 between the shoulder formed by the larger part of the rod 17 and the lever 23. The lever 23 carries at its outer end an armature 26 of magnetic material which when the lever is in the position 20 shown in full lines bridges the poles of an electromagnet 27 energized by a coil 28. This magnet may be secured either to the frame 2 or directly to the back board 1 and may be 25 of any suitable form. The face of the armature 26 or the pole faces of the magnet 27, or both, may be covered with a thin sheet of phosphor-bronze in order to prevent sticking of the armature to the magnet when the latter is deenergized. The steel disk 6 and the fixed contacts 7 and 8 may be silver plated on their coöperating surfaces for the 30 same reason and in order to insure good electrical contact at these points. The last two 35 mentioned expedients are well-known.

The operation of the device is as follows: When current passes through the actuating coil 3, which may be connected in series with the coils 12 and 13 and the contacts 7 40 and 8 as shown, the core 5 rises into the magnetic field produced, and if the magnet 27 is deenergized the lever 23 will be lifted to the position shown in dotted lines. The air gap between the top of the movable core 45 5 and the fixed core 15 will then be small and a current of a certain value in the coil 4 will be required to hold the core in this raised position after the disk 6 has broken engagement with contacts 7 and 8, thereby 50 interrupting the circuit through the coil 3. If, however, the magnet 27 is energized prior to the energization of the actuating coil 3, the armature 16 will be held down in engagement with the magnet and the lever 55 23 will be engaged by the washer 25 and will serve to stop the upward movement of the core 5. The core 5 will, therefore, have a new limit to its upward movement and the gap existing after operation between the top 60 of the core 5 and the bottom of the core 15 will be greater than it was when the core was free to move upward its maximum amount unimpeded by the lever 23. By increasing in this way the gap which exists 65 between the cores 5 and 15 when the core 5

is in its upper position, the permeability of the magnetic circuit of the holding coil 4 is decreased and a larger current is required in the coil 4 to hold the core 5 in its upper position. This means that when a relay 70 equipped as shown is used as a notching relay in a system of control, it may be controlled from a distance by energizing or deenergizing the magnet 27 and will give two limits beyond which if the current in 75 the motor circuit is increased, further cutting out of resistance will be prevented. By locating the switch which controls the energization of the coil 28 near the point from which the operator controls the system the 80 change is easily made from operation at one current limit to operation at the other.

What I claim as new and desire to secure by Letters Patent of the United States, is,

1. In a switch, a current carrying coil, a 85 core movable in the field thereof, means for moving said core into the field of said coil, and means operable from a distance for varying the permeability of the magnetic circuit of said coil. 90

2. In a switch, a current carrying holding coil, a core movable in the field thereof, means for moving said core into the field of said holding coil, and means operable from a 95 distance for varying the permeability of the magnetic circuit through the movable core.

3. In a relay, a current carrying actuating coil, a current carrying holding coil, a core movable in the fields of said coils and arranged to be moved by said actuating coil 100 and held by said holding coil, and means operable from a distance for varying the permeability of the magnetic circuit of the holding coil.

4. In a relay, a current carrying actuating 105 coil, a current carrying holding coil, a core movable in the fields of said coils and arranged to be moved by said actuating coil, and held by said holding coil, and means operable from a distance for varying the 110 limit of movement of said core in the field of said holding coil.

5. In a relay, a current carrying actuating coil, a current carrying holding coil, a core movable in the fields of said coils, and arranged to be moved by said actuating coil and held by said holding coil, a fixed core of magnetic material toward which the movable core moves, and means operable from a 115 distance for varying the gap existing between the movable and fixed cores when the movable core has been moved to its extreme 120 position towards said fixed core.

6. In a relay, a current carrying actuating coil, a current carrying holding coil, a core 125 of magnetic material movable in the fields of said coils and arranged to be moved by said actuating coil and held by said holding coil, a fixed core of magnetic material toward which said movable core moves, and 130

means operable from a distance for varying the limit of movement of the movable core toward the fixed core.

7. In a relay, a current carrying actuating coil, a current carrying holding coil, a core of magnetic material movable in the fields of said coils and arranged to be moved by said actuating coil, a fixed core toward which said movable core moves, and electro-
10 magnetically operated means for varying the gap existing between said movable and fixed cores after said movable core has been moved to its extreme position toward said fixed core.
- 15 8. In a relay, a current carrying actuating coil, a current carrying holding coil, a core of magnetic material movable in the fields of said coils and arranged to be moved by said actuating coil and held by said holding
20 coil, a fixed core of magnetic material toward which said movable core moves, and

electromagnetically operated means for varying the limit of movement of said movable core toward said fixed core.

9. In a notching relay, an actuating coil, 25 a current carrying holding coil, a core of magnetic material movable in the fields of said coils, contacts opened by said core in rising, magnetizing coils connected in series with said actuating coil and said contacts 30 and arranged to produce a magnetic field through said contacts, a fixed core toward which said movable core moves, and electromagnetically operated means for varying the limit of movement of said movable core 35 toward said fixed core.

In witness whereof, I have hereunto set my hand this 21st day of April, 1908.

ARCHIBALD S. CUBITT.
